UNITED STATES PATENT OFFICE.

JOHN NASH, OF NORTH YAKIMA, WASHINGTON, ASSIGNOR OF ONE-HALF TO DOLLIE NASH, OF NORTH YAKIMA, WASHINGTON.

CENTRIPETAL ENGINE.

1,043,962.

Specification of Letters Patent. Patented Nov. 12, 1912.

Application filed June 22, 1912. Serial No. 705,292.

To all whom it may concern:

Be it known that I, JOHN NASH, a citizen of the United States, residing at North Yakima, in the county of Yakima and State 5 of Washington, have invented a new and useful Centripetal Engine, of which the following is a specification.

The present invention relates to centripetal engines, the primary object of the invention being the provision of an engine of 10 this character, in which the rotor is provided with a plurality of tangentially disposed pockets, the inner ends of which terminate in outwardly spilling exhaust ports, 15 there being disposed in each pocket a plurality of steam channel forming blades, the outer ends of which are disposed to terminate at the periphery of the rotor while the inner ends terminate at a point to provide a clear and open exhaust port.

A further object of the present invention is the provision of an engine of this character, the stator of which is composed of two sections, having oppositely disposed 20 exhaust channels leading from the center thereof and a plurality of tangentially disposed induction ports, while the rotor is provided with a plurality of radial pockets into which are insertable packages of spaced 25 blades which constitute an impact and steam directing means to direct the steam led thereto through the induction ports to centrally disposed exhaust ports of the rotor and finally into the oppositely disposed 30 exhaust ports of the stator.

A still further object of the present invention is the provision of a novel construction of rotor and blades, said blades being so constructed and arranged, as to be readily 35 introduced into and removed from the tangential pockets of the rotor, said blades being so constructed as to permit of the greatest impact surface, and at the same time provide means for splitting the stream of steam 40 or other pressure fluid into minute streams, so that the maximum amount of impact and expansive force from the steam will result 45 prior to the exhausting thereof from the central portion of the rotor.

With the foregoing and other objects in view which will appear as the description proceeds, the invention resides in the combination and arrangement of parts and in the details of construction hereinafter 50 described and claimed, it being understood

that changes in the precise embodiment of the invention herein disclosed can be made within the scope of what is claimed without departing from the spirit of the invention.

In the drawings—Figure 1 is a side elevation of the main portion of the engine one-half of the head being removed to show a portion of the rotor in elevation. Fig. 2 is a section taken on line 2—2 of Fig. 1. Fig. 3 is a section taken on line 3—3 of Fig. 4. Fig. 4 is a section taken on line 4—4 of Fig. 3. Fig. 5 is a detail view of one bundle of blades *per se*.

Referring to the drawings, the numeral 1 designates the stator which is composed of 70 lower member 2 and the upper member 3, said members being properly coupled together to provide a steam tight joint therebetween, each of said members being provided with two steam induction ports 4, 75 which are disposed at a tangent to the inner peripheral wall of the rotor chamber 6, which is preferably made cylindrical in shape. Led to the respective tangentially disposed induction ports 4 are the steam or 80 pressure fluid conduits 5, there being four in the present instance.

It will be noted that the induction ports 4 are narrowed when compared to the cross sectional area of its respective conduits 5, 85 but that each is elongated approximately the full width of the active surface of the rotor R so that the pressure fluid or steam is properly conveyed to the periphery of the rotor R so as to act upon the full active peripheral surface thereof, as will presently appear.

The rotor R is keyed upon and rotatable with the shaft 7 and consists primarily of the three disks 8, 8' and 8'' which are properly tied together by means of the tie bolts 24, the intermediate spiders 9 being disposed between the respective disks and so formed as to provide the outer curved webs 10 and the plurality of tangentially disposed blade pockets 11 for the reception of the bundles 12 of steam receiving blades, the inner ends of said blades terminating as shown to provide the exhaust ports 13 at the extreme 95 inner ends of the respective tangential pockets 11. The exhaust ports 13 register at all times with the oppositely disposed exhaust ports 14 and 14' of the stator, there being two series of spiders 9, the disk 8' being so disposed as to form a central partition to 100 110

prevent the passage of the pressure fluid toward the transverse center of the rotor.

- Upon the outer face of each of the respective disks 8 and 8" are disposed the concentric packing rings 16, which have led there-to the ducts 17, whereby the pressure fluid admitted to the respective tangential pockets 11 will normally tend to push the packing rings outwardly into contact with the adjacent face of the stator and thus provide a steam tight joint to prevent the passage of the pressure fluid directly to the exhaust ports 14 or 14' or any back pressure from the exhaust.
- 15 The blades 18 are so constructed and secured together as to provide a plurality of steam channels 19, said channels due to the shape of the opposite walls 21, 22 and 23 of the respective pockets 11 being tangentially disposed and emptying into the exhaust port 13, the tie bolts 20 being employed to hold the blades in such spaced relation and to permit of the ready withdrawal or insertion of the bundle within its respective 25 pocket 11.

Although the packages of blades have been illustrated with the blades having the planes of the body portion disposed tangentially to the periphery of the rotor R, it is evident that the same may be disposed in bundles with their planes parallel to the faces of the disks 8, 8' and 8", it simply being desirable to produce a plurality of means for dividing the stream of pressure fluid or steam into a plurality of jets to receive from such steam or pressure fluid the maximum impact and expansive force during its passage from the peripheral outer end of the packages of blades into and through the exhaust ports 13 of the rotor. This form of package is clearly illustrated in Fig. 5.

From the foregoing description, taken in connection with the drawing it is evident that a centripetal engine constructed according to and embodying the present invention, provides a means whereby the pressure fluid is received or projected into the respective blade pockets tangentially to the rotor periphery, and that exhaust takes place at the center of the rotor without impeding in any manner the rotation thereof.

What is claimed is:

1. A centripetal engine, having a stator provided with a rotor chamber, and a plurality of induction ports tangentially of the chamber, a rotor mounted in the chamber and provided with a plurality of tangentially disposed pockets open at the periphery and to one side of the center of the rotor, 50 and a plurality of bundles of spaced blades, one bundle to each pocket, carried by the rotor.

2. A centripetal engine, having a stator provided with a rotor chamber having a 65 plurality of tangentially disposed induction

ports and oppositely disposed exhaust ports, a rotor mounted in the chamber and having a central partition disk, and two end disks, two spiders one upon each side of the central disk, each spider providing a plurality of pockets disposed tangentially to the periphery of the rotor, the outer disk being provided with an eduction port alining with the respective exhaust ports of the chamber.

3. A centripetal engine, having a stator provided with a rotor chamber having a plurality of tangentially disposed induction ports and oppositely disposed exhaust ports, a rotor mounted in the chamber and having a central partition disk, and two end disks, two spiders one upon each side of the central disk, each spider providing a plurality of pockets disposed tangentially to the periphery of the rotor, the outer disk being provided with an eduction port alining with the respective exhaust ports of the chamber, and a package of spaced pressure fluid receiving blades disposed in each pocket.

4. A centripetal engine, having a stator provided with a rotor chamber having a plurality of tangentially disposed induction ports and oppositely disposed central exhaust ports, the outer ends of the induction ports being of substantially the same width as the rotor chamber; a rotor mounted in the chamber and having a central partition disk, two end disks, and two spiders one upon each side of the central disk; each spider providing with the disks a plurality of tangentially disposed pockets open to the periphery of the rotor and providing two series of pockets to the rotor; and tie bolts for clamping the disks and spiders together, and the outer disk being provided with centrally disposed eduction ports in communication with the lower inner ends of the pockets of its respective spider and alined with the respective exhaust port of the stator.

5. A centripetal engine, having a stator provided with a rotor chamber having a plurality of tangentially disposed induction ports and oppositely disposed central exhaust ports, the outer ends of the induction ports being of substantially the same width as the rotor chamber; a rotor mounted in the chamber and having a central partition disk, two end disks, and two spiders one upon each side of the central disk, each spider providing with the disks a plurality of tangentially disposed pockets open to the periphery of the rotor and providing two series of pockets to the rotor; tie bolts for clamping the disks and spiders together, and the outer disk being provided with centrally disposed eduction ports in communication with the lower inner ends of the pockets of its respective spider and alined with the respective exhaust port of the stator; and a 130

plurality of packages of pressure fluid receiving blades, one package to each tangential pocket of the rotor mounted therein and extending from the periphery to a point 5 near the inner end of its respective pocket to provide an exhaust space at the inner end of the pocket.

6. A centripetal engine, having a stator provided with a rotor chamber having a 10 plurality of tangentially disposed induction ports and oppositely disposed central exhaust ports, a rotor mounted in the chamber and having a central partition disk, and two end disks, two spiders one upon each side of 15 the central disk, each spider providing a plurality of pockets disposed tangentially to the periphery of the rotor, the outer disk being provided with an eduction port alining with the respective exhaust ports of the 20 chamber, and a concentric packing ring mounted upon the outer face of each disk between the outer peripheral wall of the rotor chamber and the exhaust ports thereof.

7. A centripetal engine, having a stator 25 provided with a rotor chamber having a plurality of tangentially disposed induction ports and oppositely disposed central ex-

haust ports, the outer ends of the induction ports being of substantially the same width as the rotor chamber; a rotor mounted in 30 the chamber and having a central partition disk, two end disks, and two spiders one upon each side of the central disk, each spider providing with the disks a plurality of tangentially disposed pockets open to 35 the periphery of the rotor and providing two series of pockets to the rotor; tie bolts for clamping the disks and spiders together, and the outer disks being provided with centrally disposed eduction ports in communication with the lower inner ends of the 40 pockets of its respective spider and alined with the respective exhaust ports of the stator, and a concentric packing ring mounted upon the outer face of each disk between the 45 outer peripheral wall of the rotor chamber and the exhaust ports thereof.

In testimony that I claim the foregoing as my own, I have hereto affixed my signature in the presence of two witnesses.

JOHN NASH.
